UNITED STATES PATENT OFFICE.

ALVA G. ROBERTS, OF ERIE, KANSAS.

JAR FOR REMOVING STANDING VALVES.

Application filed October 24, 1923. Serial No. 670,567.

To all whom it may concern:

Be it known that I, ALVA G. ROBERTS, a citizen of the United States, residing at Erie, in the county of Neosho and State of Kansas, have invented a new and useful Jar for Removing Standing Valves, of which the following is a specification.

The object of my invention is to provide an improvement in apparatus used in oil well drilling machinery for use in removing valves from oil well pumps and which provides novel means for giving a jerk or jar to the valve whereby it may be removed quickly and easily; and to provide the novel combination and arrangement of parts disclosed in the accompanying drawings, in which:—

Figure 1 is a vertical section through my invention with plunger 7 at the end of its stroke;

Fig. 2 is a section on line 2—2 of Fig. 1 with plunger 7 in its raised position;

Fig. 3 is a top plan view; and

Fig. 4 is a transverse section on line 4—4 of Fig. 1.

Like numerals indicate like parts throughout the several views.

Referring to the accompanying drawings, I provide a tube 1 having a tapered lower end 2 provided with external screw threads 3. The inner portion of the upper end of the tube is provided with an annular shoulder 4 and a short central channel 5. Loosely and slidably mounted in tube 4 is a plunger 35 or jar 7 having a plunger head 10 on its lower end, the lower end of this plunger head having bifurcated ends 11 adapted to engage around the pin 6 which extends transversely through and is fixed in the lower 40 end of the tube 1, as shown in Figs. 1 and 2. The upper end of plunger 7 is provided with an angular wrench head 9 above which is a screw-threaded cylindrical end portion 8.

In operation, the threaded end of the plunger is screwed into the sucker rod of the oil drilling machinery and the external bottom threaded end 3 of the pipe 1 is screwed into the standing valve which is to be removed, the engagement of the bifurcated end of plunger head 10 over the pin 6 which extends through the lower end of the pipe 1 permitting of turning the pipe for screwing the lower end into the top of the standing valve. The annular shoulder 4 at the upper end of the pipe prevents the plunger from being withdrawn entirely from the tube.

When the plunger is screwed on the end of a sucker rod it will move freely from the pin 6 toward the top or annular shoulder 4 over a distance of about 12 inches before it 60 will cause any pressure on the standing valve. The plunger is allowed to drop, giving a jerk or jar on the pipe and consequently on the standing valve which has the effect of loosening it, although it may fit ever 65 so tightly, permitting its quick and easy removal. The device is one that is most useful to persons engaged in the pumping and care of oil wells.

What I claim is:—

1. A jar for removing the standing valve of oil well apparatus, comprising a pipe having an externally threaded lower end, a plunger slidably mounted in the pipe, said plunger having a bifurcated plunger head, 75 a pin extending transversely through and fixed in the lower end of the pipe over which the bifurcated end of the plunger head engages, means for preventing withdrawal of the plunger from the pipe, and 80 means for attaching the upper end of the plunger to suitable operating means.

2. In a device of the class described, the combination of a pipe having an internal annular shoulder at its upper end, and having a tapered externally threaded lower end 85 adapted to be screwed into the standing valve, a pin extending transversely through the lower end of the pipe, a plunger slidably mounted in the pipe and having a bifurcated plunger head adapted to engage around the transverse pin when the plunger is in its lowermost position and adapted to abut against the annular shoulder when in its raised position, and means for attaching 90 the plunger to suitable operating means.

3. In a device of the class described, the combination of a pipe having an internal annular shoulder at its upper end, and having a tapered externally threaded lower end 100 adapted to be screwed into the standing valve, a pin extending transversely through the lower end of the pipe, a plunger slidably mounted in the pipe and having a bifurcated plunger head adapted to engage 105 around the transverse pin when the plunger is in its lowermost position and adapted to abut against the annular shoulder when in its raised position, the plunger having a threaded upper end and having an angular 110 wrench-engaging portion near its upper end.

ALVA G. ROBERTS.
